UNITED STATES PATENT OFFICE.

ERNEST FRANKLIN, OF PORTLAND, OREGON.

GAS-ENGINE.

No. 860,651.

Specification of Letters Patent.

Patented July 23, 1907.

Application filed November 28, 1905. Serial No. 289,464.

To all whom it may concern:

Be it known that I, ERNEST FRANKLIN, a citizen of the United States, residing at Portland, in the county of Multnomah and State of Oregon, have invented new 5 and useful Improvements in Gas-Engines, of which the following is a specification.

This invention relates to gas engines, and has for its objects to produce a comparatively simple, inexpensive device of this character in which the piston will be 10 positively driven during both its in and out stroke, one wherein the movement of the piston in one direction serves to compress an explosive charge for driving the piston in the other direction, and one wherein the explosive gas or fluid will be alternately drawn into 15 the separate compartments or chambers.

A further object of the invention is to provide an engine of this type comprising a pair of pistons connected for simultaneous movement, one wherein a charge of explosive fluid is admitted behind the piston 20 on its out-stroke for compression on its in-stroke, and one wherein the movement of one piston to compressing position operates a valve for admitting a charge to the other piston.

With these and other objects in view, the invention 25 comprises the novel features of construction and combination of parts more fully hereinafter described.

In the accompanying drawings: Figure 1 is a central longitudinal section through an engine embodying the invention. Fig. 2 is a transverse section taken on 30 the line 2—2 of Fig. 1. Fig. 3 is a similar view taken on the line 3—3 of Fig. 1.

Referring to the drawings, 1 designates a tubular casing subdivided by a central web or partition 2 into a pair of compression compartments 3 and inclosing an 35 inner tubular member 4 in turn divided by a central partition 5 into a pair of cylinders 6, hereinafter termed respectively the front and rear cylinders, the casing 1 being closed by end members or heads 7 provided respectively with tubular extensions 8, 9, of which the 40 former is closed at its outer end while the outer end of the latter is open and provided with opposed bearings 10 in which is journaled the main drive shaft 11 having an eccentric or crank portion 12.

Slidably disposed on the member 4 and at opposite 45 sides of the partition 2 is a pair of tubular piston members 13, 14, having heads 15 designed to fit in the chambers 6 and provided with marginal webs or flanges 16 fitted in the casing 1 to work in the compartments 3, the piston members being connected for simultaneous 50 movement by means of connecting rods or elements 17 extended through and slidably disposed in suitable bearing openings 18 formed in the partition 2, there being formed in each of the members 13 or 14 and around the adjacent head or piston proper 15 a passage 55 19 terminating at its outer end in a laterally-opening port 20 designed to register with an exhaust opening

or port 21 formed through the wall of the adjacent extension 8 or 9, while formed at the outer ends of the compartments 3 are openings or ports 22 leading to the external atmosphere and through the medium of which 60 air pressure within the compartments is relieved, as and for a purpose hereinafter explained.

Formed in the walls of the piston members 13, 14, and at points adjacent the inner ends of the latter are lateral openings or ports 23 leading from the compartments 3 and adapted to register with ports or passages 24 formed in the partition 5 and communicating respectively with the cylinders 6, said passages being terminated at their inner ends in valve seats 25 designed to receive puppet valves 26 having stems 27 extended in relatively reverse directions through suitable bearing openings in the partition 5 and projected respectively into the opposite cylinders 6, there being provided on the outer end of each stem a head or button 28 between which and the partition 5 is arranged a normally expanded spring 29 acting to maintain the valve in closed position, it being noted in this connection that the arrangement of the valve stems is such that the piston 15 working in one cylinder 6 will open the valve leading to the other cylinder, as and for a purpose more fully hereinafter 70 explained.

Leading to the casing 1 is a gas supply pipe or duct 30 having a pair of branch portions 31 communicating respectively with the compartments 3 through the medium of openings or ports 32, there being arranged in 85 the branches 31 inwardly opening check valves 33 designed to normally close communication between the pipe 30 and casing and to open as usual under the action of suction created in the compartments 3 and against the action of springs 34 for admitting the explosive 90 fluid to said compartments.

Pivotedly connected with the piston member 14 by means of a pin 35 is a connecting rod 36 extended centrally through the extension 9 and having its other end journaled on the crank portion 12 of shaft 11 for operating the latter during the operation of the pistons 13, 14, as usual in devices of this class.

In practice, upon each stroke of the connecting rod 36, a charge is compressed in one of the cylinders 6 and a fresh charge admitted to the other cylinder for compression upon reverse movement of the pistons, while at the same time a charge of gas is drawn into one of the compartments 3 for compression therein and final admittance to the first named cylinder. For instance, upon instroke of the connecting rod 36, as shown in Fig. 1, a charge of gas is compressed in the forward cylinder 6 and the dead gases and other products of explosion are at the same time exhausted from the rear cylinder 6 through the passage 19 and ports 20 and 21, while at the same time the valve 26 which controls communication between the rear cylinder and forward compartment 3 is opened at the completion of the 105 110

instroke of the connecting rod to permit a fresh charge of gas which during rearward movement of the pistons has been compressed in the forward compartment to be admitted to the rear cylinder. Upon outstroke of the 5 connecting rod under the impulse of explosion of the previously compressed charge within the forward cylinder 6, the charge of gas within the rear cylinder is compressed and at the completion of the forward movement of the pistons the other valve 26 controlling communication between the forward cylinder 6 and rear compartment 3 is opened to permit a fresh charge of gas which has been compressed in the rear compartment to flow into the forward cylinder from which latter the products of explosion are previously exhausted 10 through the passage 19 and ports 20 and 21, as before explained. Upon movement of the pistons on the instroke of the connecting rod, a charge of gas is taken into the rear compartment from the duct 30 for compression through the reverse stroke of the pistons and 15 to be finally delivered into the forward cylinder, while on the outstroke of the connecting rod a charge of gas is taken from the duct 30 into the forward compartment and compressed therein and finally delivered into the rear cylinder on the instroke of the rod. 20

25 It is to be understood that at the completion of each stroke of the connecting rod a charge is exploded in one of the cylinders for driving the rod through its reverse or return stroke whereby the rod is positively driven throughout each stroke and further that the ports 22 serve to relieve air pressure in the chambers 3 behind the compression pistons or flanges 16.

Having thus fully described my invention, what I claim is:

1. In an explosive engine, a casing containing an inner 35 tubular member and having a transverse partition dividing the space outside of said member into front and rear compression compartments provided with inlet relief ports, a wall or partition disposed in said member and di-

viding the same into front and rear cylinders, said wall being provided with passages arranged to connect the 40 front and rear compartments respectively with the rear and front cylinders, valves for closing said passages and having reversely extended stems projecting respectively into the opposite cylinders, tubular piston members slidably disposed on said tubular member and containing 45 heads designed for entrance into the adjacent cylinders, a valve-controlled supply duct communicating with the inlet ports for admitting a motive fluid to the compartments, exhaust ports leading from the cylinders, a drive shaft journaled at one end of the casing, a pitman connection between said shaft and the adjacent piston member, and means connecting the piston members for simultaneous movement.

2. In an explosive engine, a casing containing an inner, tubular member and having a transverse partition dividing the space outside of said member into front and rear compression compartments having inlet and relief ports, a wall or partition disposed in the member for subdividing the same into front and rear cylinders, said wall being provided with passages arranged to connect the front and 55 rear compartments for communication respectively with the rear and front cylinders, spring pressed valves arranged for normally closing said passages and having stems projected through the wall respectively into the opposite cylinders, a valve-controlled supply duct communicating with the inlet port for admitting motive fluid to the compartments, tubular piston members slidably disposed on the inner member and having heads designed for entrance into the adjacent cylinders, said piston members being provided with external, marginal flanges disposed 60 respectively in the compartments and constituting compression pistons, connecting rods slidably extended through the transverse partition and connecting the pistons for movement one with the other, exhaust ports provided in the casing leading from the respective cylinders, a drive 65 shaft journaled at one end of the casing and a pitman connection between the shaft and adjacent piston member.

In testimony whereof, I affix my signature in presence of two witnesses.

ERNEST FRANKLIN.
